UNITED STATES PATENT OFFICE.

ALGER L. DRAKE AND DELL R. SMITH, OF BELLINGHAM, WASHINGTON.

TOBACCO-PIPE.

No. 923,419.

Specification of Letters Patent.

Patented June 1, 1909.

Application filed May 28, 1908. Serial No. 435,501.

To all whom it may concern:

Be it known that we, ALGER L. DRAKE and DELL R. SMITH, citizens of the United States, and residents of Bellingham, in the county of Whatcom and State of Washington, have invented certain new and useful Improvements in Tobacco-Pipes, of which the following is a specification.

Our invention relates to an improvement in tobacco pipes and consists in separating the main body of the pipe in two sections on a medial surface along the duct, and providing ready and secure means of joining the two sections together.

The object of our invention is to provide for the quick and easy cleaning of the pipe, also to cool the smoke while it is yet in the duct of the pipe. We accomplish these objects by the construction and devices illustrated in the accompanying one sheet of drawings in which similar characters refer to similar parts.

Figure 1 is a partly sectionalized side elevation of a tobacco pipe. Fig. 2 is a plan view of a separable portion of the same. Fig. 3 is an end elevation of a transverse section on a plane through the line $x-y$, Fig. 1.

1 is the main part or body of the pipe. 2 is the lower part of the same and is joined to the main body on a horizontal plane through the center of the main duct 7, 8.

3 is a mouthpiece.

4 is the ferrule which is slightly conical and is fastened to the stem part of the main body.

Centrally located in the lower part of the bowl is the pit 9. Between this pit and the mouthpiece are the pits 11, 11, 11. The duct 13 encompasses pit 9 in part 2 and enters duct 7 near the pits 11, 11, 11. A wire prong 5 is secured in part 2 in the bottom of pit 9, rises on an incline toward the right hand, lies in a groove in the side wall of pit 9, and reaches a groove 10 in part 1 where its right hand end is curved downward. When in operative position, the prong 5 engages in a staple 6 secured in part 1. The relation of prong 5 and staple 6 are such that when part 2 registers with part 1 and these two parts are closely pressed together, said prong has entered said staple as far as it can go. At the same time, the right hand end of part 2 has entered the conical ferrule 4 so far that this end of part 2 is also closely pressed against part 1.

When it is desired to remove part 2 from part 1, it is moved toward the left hand position indicated in dotted outline at 2', when prong 5 is disengaged from staple 6 and the two parts may be separated. The object of separating the pipe at this place is to afford ready means for thoroughly cleaning the same. The pits 9, 11, 11, 11 serve to retain the liquids which are formed in the pipe when in use, and the duct 13 serves the same purpose. The groove 10 serves to direct the prong into the staple and the curved end of the prong reaches the curved end of this groove before it is quite home, thus pressing this end of the prong downward against the staple. The location of the prong and staple in the duct 7, 8 serves the purpose of a screen in preventing fine particles of tobacco from entering the mouth-piece. When secured as shown in Fig. 1, the two parts 1 and 2 are united with practically an air tight joint. However, it is found desirable that a small amount of air enter the pipe at this joint as it serves to cool the smoke and cause the precipitation of the undesirable liquids therefrom.

Having thus described our invention, what we claim as new and desire to secure by Letters Patent is,

1. In a tobacco pipe, separable into a major and a minor part on a common surface along the duct of the same, the combination of said separable parts, one or more pits or depressions in that portion of the duct in said minor part, and means for clamping said parts in operative union.

2. In a tobacco pipe, separable into a major and a minor part on a common surface along the duct of the same, the combination of said separable parts, one or more pits or depressions in that portion of the duct in said minor part, an outlying groove in said minor part which encompasses the bowl end of said duct, and means for clamping said parts in operative union.

3. In a tobacco pipe, separable into two parts on a common surface along the duct of the same, the combination of said separable parts, a staple or similar holding device attached to one of said parts, and a prong or hook attached to the other of said parts, said prong engages with said staple when said parts are moved together on said common surface.

4. In a tobacco pipe, separable into a major and a minor part on a common sur-

face along the duct of the same, the combination of said separable parts, a prong or hook attached to one of said parts, a staple or similar holding device attached to the other of said parts, and a conical ferrule attached to the major of said parts, said prong engages with said staple and said minor part enters said ferrule when the two parts are moved together on said common surface.

5. In a tobacco pipe, separable into a major and a minor part on a common surface along the main duct of the same, the combination of said parts, a prong or hook attached to said minor part, a staple or similar holding device attached to said 10 major part, a conical ferrule attached to

said major part, one end of said minor part is suited to enter said ferrule, pits in the main duct in said minor part, a duct in said minor part which encompasses a portion of 20 said main duct, a groove in the duct in said major part, said groove passes between the sides of said staple, and a mouth piece fitted into said main duct.

Signed at Bellingham in the county of 25 Whatcom and State of Washington this twenty-second day of May A. D. 1908.
